UNITED STATES PATENT OFFICE.

ABRAHAM J. SPRINGER, OF PHILADELPHIA, PENNSYLVANIA.

DESIGN FOR A DISPLAY-TRAY.

SPECIFICATION forming part of Design No. 35,475, dated December 24, 1901.

Application filed September 28, 1901. Serial No. 76,962. Term of patent 7 years.

To all whom it may concern:

Be it known that I, ABRAHAM J. SPRINGER, a citizen of the United States, residing at Philadelphia, in the county of Philadelphia and 5 State of Pennsylvania, have invented and produced a new and original Design for Display-Trays, of which the following is a specification, reference being had to the accompanying drawings, forming part thereof.

Figure 1 is a perspective view of a display-tray, showing my new design. Fig. 2 is a top plan view of the same, and Fig. 3 is a sectional view taken on the line 3 3 of Fig. 2.

As shown in the drawings, the leading or 15 material feature of my design is found in the rhombic-shaped bottom A with the straight sides B, having angular intersections, the sides extending upwardly and outwardly

from the bottom and the upper edges forming a rhombic-shaped outline. The bottom A 20 is provided with the bead a, and the straight sides B have the bead b around the edges thereof.

Having described my invention, what I claim as new, and desire to secure by Letters 25 Patent, is—

The design for a display-tray substantially as shown and described.

In testimony whereof I have signed my name to this specification in presence of two 30 subscribing witnesses.

ABRAHAM J. SPRINGER.

Witnesses:

JOHN THIEL,
PERCIVAL H. GRANGER.
